PERMANENT WAVING APPARATUS

Hobart N. Durham, Munsey Park, N. Y., and George B. Finnegan, Jr., Mountain Lakes, N. J., assignors, by mesne assignments, to Eugene, Ltd., New York, N. Y., a corporation of New York

Application June 21, 1933, Serial No. 676,788

8 Claims. (Cl. 219—24)

The present invention relates to permanent waving and more particularly to a novel and improved process of and apparatus for subjecting a wound tress of hair to heat, moisture and other agents to effect permanent waving thereof.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

15 The accompanying drawing, referred to herein and constituting a part hereof, illustrates one embodiment of the invention, and together with the description, serves to explain the principles of the invention.

20 Of the drawing:

Figure 1 is a cross section illustrating a typical embodiment of the present invention and also showing the manner in which the process of the present invention is carried out;

25 Figure 2 is a side elevation of the embodiment shown in Figure 1;

Figure 3 is an end elevation of the embodiment shown in Figure 2, with certain parts moved to different positions, and other parts being omitted;

30 Figure 4 is a perspective view of a heating and lotion-carrying pad for use in practicing the present invention, with certain parts broken away; and

Figure 5 is a cross section through a modified embodiment of the invention.

35 The present invention has for its object the provision of a novel and improved heating device for heating wound tresses of hair in the permanent waving process. Another object of the invention is the provision of such a device in which the heater elements are inexpensive, readily renewed and adapted to be used but a single time. A further object is the provision of a heater element moistened with a permanent waving lotion 40 or fluid and adapted to be pressed into intimate contact with the wound tress of hair. Still another object of the invention is the provision of a novel and improved process of heating the wound tress and subjecting it to the action of moisture and other softening agent.

45 In accordance with the illustrative embodiment of the invention, the heating apparatus comprises a pair of parti-cylindrical members adapted to surround and be pressed together against the wound tress of hair, and means are preferably

provided for securing a lotion saturated pad within the concavity formed by said members so that it is pressed into intimate contact with the hair and insures efficient application of heat and moisture to the wound tress. Preferably, and as 5 embodied, the heating element comprises an electrolytic heater in which the electric circuit is completed by the ionized hair waving lotion, so that all of the advantages of the electrolytic hair waving process are fully realized.

10 Although the invention is shown in connection with the waving of hair wound in croquignole fashion, the invention is equally applicable in its principal features to hair which is wound helically or from the roots towards the ends.

15 It will be understood that the foregoing general description and the following detailed description as well are exemplary and explanatory of the invention but are not restrictive thereof.

20 Referring now in detail to the illustrative embodiment of the invention as shown in the accompanying drawing, the heating pad preferably comprises a sheet of relatively thin metal foil 10, a slightly larger sheet of moisture-absorbent material 11, such as flannel or felt, and 25 a sheet of perforate metal foil 12 which may be provided with a projecting terminal or tab 13 formed integrally with the sheet 12. If desired, one edge of the absorbent sheet may be folded over the edge of the foil 12 to provide an insulated 30 margin 14, and a narrow strip of absorbent material or paper 15 may be provided along the opposite edge of foil 12. The several pieces are assembled in the position shown in Figure 4, with the absorbent sheet 11 positioned between the 35 metallic foils 10 and 12, and the marginal strips 14 and 15 secured to the foil 12 on its side away from the absorbent material 11 by lines of stitching 16 and 17. If desired, and in order to 40 separate the perforate foil 12 from the hair to be waved, a sheet of thin paper, perforated in register with the foil 12 and secured thereto, may be provided on the side of the foil away from the absorbent material 11.

45 As is usual in the croquignole waving of hair, the hair is wound from the points to its roots on the curling rod or pin 20, and is clamped closely adjacent to the scalp between the clamping members 21 and 22. The roller and clamp may be of the conventional or any desired form, and 50 need not be described in detail. The curling pin 20 is preferably slightly longer than the sheet of absorbent material 11, and the absorbent sheet 11 is preferably of sufficient width to extend 55 from clamping member 22 around the wound

tress of hair and to the clamping member 22, as shown in Figure 1 of the drawing.

Means are provided for pressing the curl heating pad into close contact with the wound tress 5 of hair to be waved, and for maintaining it on the wound tress during the heating process. For this purpose, a clamp is provided which comprises a pair of parti-cylindrical members 25 and 26 formed of molded insulating material, pivoted together by means of a pivot pin 27, and pressed inwardly by means of springs 28 secured at their ends to members 25 and 26 by headed pins 29.

One of the members, 25, is provided with a handle portion 30 formed integrally therewith, and having suitable channels 31 through which wires 32 may be threaded. Channel 31 is provided with an enlarged portion 33 to receive the metal clamp 34 clamping the wires 32 together and serving to prevent any pull being transmitted beyond it to the ends of the wires. The small knob 35 is fastened, by suitable screws, to the upper portion of handle member 30.

Means are also provided for supplying power 25 to the sheets of foil 10 and 12, and for this purpose a resilient contact member 40 is embedded in a suitable recess in member 26, and is connected with one of the wires 32 by means of rivet 44 which also serves to secure the contact 30 member in position to contact with the outer sheet of foil 10. For contacting with the terminal tab 13 formed integrally with the sheet of foil 12, a metallic sheet 45 is provided on the outer surface of member 25 and is secured there- 35 to by rivets 46, also being connected to the other wire 32. Means are provided for pressing the terminal tab 13 into electrical contact with sheet 45, and for this purpose a finger 47 is pivotally mounted in lugs 48 projecting from member 25, 40 by means of pivot pin 49, and is provided with a camming surface 50 adapted to cooperate with a resilient tongue 51 formed integrally with plate 45. Camming surface 50 and tongue 51 cooperate to hold finger 47 in the position shown in 45 Figure 1, or in the position of Figure 3.

In use, the absorbent member 11 of the curl heating pad is moistened with a suitable amount of an electrolytically conducting lotion, and the curl-heating pad is then placed within the members 25 and 26 with tab 13 held against plate 45 by finger 47, the pad being shaped with the fingers so as to conform more or less to the shape of the inner surface of members 25 and 26. The clamping members 25 and 26 are then 55 pushed over the wound tress of hair, spreading themselves apart slightly and finally pressing the edges of the heating pad together into the position shown by Figure 1. The current is then turned on, and passes between the sheets of foil 10 and 12 and through the electrolytically conducting hair waving lotion contained in the absorbent sheet 11, the resistance to the passage of this current serving to heat the lotion and thereby steam the curl. When the curl has been steamed 60 for a sufficient length of time, the current is shut off, the clamp and pad removed and the permanently waved hair may then be treated 65 in the usual manner.

If desired, the sheet of foil 10 may be omitted 70 from the heating pads and may be replaced by thicker metallic electrodes 56 and 57 adapted to form a more or less permanent part of the clamping means and secured to the inner, concave faces of members 25 and 26 by rivets 55, 75 as shown in Figure 5. Electrode 56 is connected

to one wire 32 by rivet 44 and is connected to the other electrode 57 by rivets 58 and flexible connector 59. Electrodes 56 and 57 may, conveniently, be formed of a metal such as lead.

The invention is shown as particularly adapted 5 for use in connection with the process of electrolytically heating permanent waving heating pads, but in certain of its features the invention is also applicable to other permanent waving 10 processes, and in particular to those processes utilizing a flexible metallic resistance element in 15 the heating pads.

The invention in its broader aspects is not limited to the specific mechanisms shown and described but departures may be made therefrom 15 within the scope of the accompanying claims without departing from the principles of the invention and without sacrificing its chief advantages.

What we claim is:

1. A heating appliance for the permanent waving of living human hair including in combination a clamp to be positioned around and closely adjacent to a wound tress, a pair of electrodes conforming in general to the shape of 25 the wound tress and absorbent moisture-containing material separating said electrodes and pressed into contact therewith when said clamp is positioned on said tress, means for attaching the electrodes and absorbent material to the 30 clamp in electrolytically conducting relation prior to positioning the clamp about the tress.

2. A heating appliance for the permanent waving of living human hair including in combination a clamp to be positioned around and closely adjacent to a wound tress, a pair of electrodes and absorbent material separating said electrodes and pressed into contact therewith when said clamp is positioned on said tress, said absorbent material being adapted to conduct current between said electrodes and through said material 35 when said material is moistened and means for attaching the electrodes and absorbent material to the clamp in electrolytically conducting relation 40 prior to positioning the clamp on the tress. 45

3. A permanent waving appliance including in combination a clamp adapted to embrace a wound tress of hair, an electrolytic lotion-applying and heating device, and means for seating and holding said device within the clamp whereby the clamp and said device may be simultaneously placed about the tress.

4. A permanent waving appliance including in combination a clamp adapted to embrace a wound tress of hair, a pliant, deformable, electrolytic lotion-applying and heating device, and means for seating and holding said device within the clamp whereby the clamp and said device may be simultaneously placed about the tress.

5. A permanent waving appliance including in combination a clamp adapted to embrace a wound tress of hair, a pliant, deformable, electrolytic lotion-applying and heating device, and means for seating and holding said device within the clamp whereby the clamp and said device may be simultaneously placed about the tress and terminals carried by the clamp for bringing electric power to said electrolytic device.

6. A permanent waving appliance including in combination an arcuate clamp having electric 70 circuit terminals and adapted to embrace a wound tress of hair, an electrolytic lotion-applying and heating device comprising an absorbent lotion-containing sheet interposed between electrode sheets, and means for attaching the electrodes 75

to said terminals and seating the electrolytic device within the clamp prior to applying the clamp and heating device to the tress.

7. A hair waving device including in combination a pliant lotion applicator and heater adapted to be applied to a wound curl including a lotion-carrying sheet member interposed with two electrode sheets, and a clamp adapted to close about the lotion applicator to compress it against the curl, the clamp having contacts adapted to contact with the electrode sheets and circuit wires connected to the clamp.

8. Permanent waving mechanism for heating and steaming a croquignole-wound curl including in combination a rod for supporting the wound

curl, protecting means between said rod and the scalp, a lotion applicator and heater comprising lotion absorbent means and spaced-apart electrodes, at least one of which is pliable and compressible and adapted to be placed in a horse-shoe shape about the portion of the curl which lies exposed above the protecting means, a clamping device adapted to overlie substantially the entire surface of said electrode about the curl and to compress and retain the electrode closely in contact with the curl and the lotion, and means connected with said clamp for connecting the electrodes to terminals of opposite polarities.
